UNITED STATES PATENT OFFICE.

EDWARD D. MCKENNA, OF NEW YORK, N. Y.

ELECTRICAL TERMINAL.

Application filed October 3, 1924. Serial No. 741,446.

This invention relates to an electrical terminal. An object of the invention is to provide an electrical terminal which is simple, durable, efficient and strong, so that when a connection has been made through the intermediary of this terminal to a wire it will remain firm and secure.

Another object of the invention is to provide a metal terminal which can be applied to the end of a stranded conductor or cable and firmly fastened thereto, and provided with means whereby the bared ends of the wire can be securely wrapped or fastened to the terminals and held firmly thereon when the terminal is applied to a binding post.

The invention is illustrated in the drawings, of which—

Figure 1 is a section through the terminal; Fig. 2 is a transverse section;

Fig. 3 is a vertical section through a modified form;

Fig. 4 is a transverse section through the same form of terminal;

Fig. 5 is a section through a still further modified form;

Fig. 6 is a section taken through another modification;

Fig. 7 is a perspective view of a further modification;

Fig. 8 is a section therethrough;

Fig. 9 is an elevation of a further modification; and

Fig. 10 is a section therethrough.

The forms of the invention shown in the drawings are preferred forms, although it is understood that other modifications in the construction and arrangement of the parts and in the character of the materials used may be adopted without departing from the spirit of the invention as set forth in the appended claims.

In generally considering this invention, the main purpose is to provide a metal terminal which will embrace the end of a cable or stranded conductor and permit the bared ends of the wires to be firmly and securely wrapped around the terminal in such manner that when the terminal is connected to a binding post and secured thereon the wires will be more securely held to the terminal by reason of this connection.

In general, the invention concerns a cup-like casing adapted to embrace the end of a cable or conductor supporting a pair of

spaced plates, these plates being provided with suitable, aligned apertures to permit of receiving the stem of a binding post. The terminal is provided with openings through the end of the cup to permit the bared ends of the wires to be passed therethrough and wrapped around, between the spaced plates. These plates may be provided with additional apertures for the purpose of passing the wires therethrough to make the wrapping more secure. When this terminal is slipped on to a binding post and the binding post is securely clamped down on the terminal, these spaced plates will be pressed more closely together and thus clamp the wires more firmly therebetween. The plates may be provided with notches or irregular surfaces to further secure the fastening of the wires thereto.

The preferred form of the invention as shown in the drawings comprises a cup-shaped metal casing 1 adapted to embrace the end 2 of a suitable conductor or cable, the ends of the wires of which are bared and adapted to pass through an aperture 3 in the end of the cup. On this end of the cup a pair of spaced plates 4 and 5 are mounted and are preferably formed integral with the cup. These plates are provided with aligned apertures 6 and 7 to receive a binding post stem, as well as with slots 8 and 9 opening into the apertures 6 and 7. The wires 10 from the conductor will pass up through the aperture 3 and can be wrapped around and between the plates 4 and 5 to secure the conductor to the terminal. As the terminal is mounted to the stem of a binding post and the pin securely clamped down, it will be observed that it will be obvious that the plates 4 and 5 will be pressed closer together, thus more securely holding the wire 10 in place.

In Figs. 3 and 4 a modified form of the invention is shown in which the cup 11 is provided with a hole 12 and spaced plates 13 and 14 having apertures 15 and 16 and auxiliary apertures 17 and 18 through which the wires may be passed to increase the effectiveness of the engagement of the wires with the terminal.

In Fig. 5 a construction somewhat similar to that illustrated in Fig. 1 is shown, with the exception that the aperture 19 leading from the cup outwardly is disposed between the two plates. This modification is also

different from Fig. 1 in that the upper side of the binding post aperture is connected to the upper edge of the plate by a slot 19^a so that the wire can be drawn down through this slot into the lower slot below said aperture.

In Fig. 6 a modification is shown in which the plates 20 and 21 are disposed at an inclined angle with respect to the cup so that this terminal can be used for particular locations.

In Figs. 7 and 8 a construction is shown similar to those previously described with the exception that the sides of the plates are provided with notches 22 to further insure the engagement of the wire. Furthermore, auxiliary openings 23 and 24 are provided rather elongated in dimensions. Also, in this case, the cap is provided with two apertures 25 and 26 for the passage of the conductors therethrough.

In the modification shown in Figs. 9 and 10, spaced plates are provided with lateral notches 27 and 28. These plates also are formed in one piece in a U-shaped manner separate from the cup, the base of the U being fastened by a rivet 29 to the cup, this

rivet providing a passage through which the conductors can be led.

It will thus be obvious that I have provided a simple, efficient, durable and strong terminal which can be readily applied to any conductor of this type to provide a firm, secure connection between the wires of the conductor or cable and the terminal and whereby the wires will be more effectively held in place as the terminal is more tightly clamped to a binding post.

What I claim is:

An electric terminal, comprising a cup-shaped casing adapted to receive the end of a cable and having an opening in the top and provided with two spaced end parallel plates extending from the top and disconnected from each other, the plates being provided with registering openings for the reception of a binding screw and with slots and about which plates and between the same, bare wires from the cable are adapted to be wound and firmly clamped between the plates when said plates are drawn together by the binding screw in securing the terminal in position.

EDWARD D. MCKENNA
